POWER-DRIVEN SURFBOARD

Doty M. Steele, Los Angeles, Calif.

Application June 25, 1945, Serial No. 601,487

6 Claims. (Cl. 9—18)

1

My invention relates to a power driven surf board and has for its principal objects, to equip a surf board of high buoyancy, with a propeller driven by an internal combustion engine, further, to provide simple and efficient means for controlling the operation of the motor and the steering of the surf board while same is being driven forwardly and further, to provide a surf board with pontoons arranged along both sides and mounted so as to be lowered onto the surface of the water and thereby increase the buoyancy of the surf board, or elevated from the water when it is desired to drive the surf board at increased speeds.

With the foregoing and other objects in view, my invention consists in certain novel features of construction and arrangement of parts which will be hereinafter more fully described and claimed and illustrated in the accompanying drawings in which:

Fig. 1 is a top plan view of my improved surf board.

Fig. 2 is a vertical longitudinal section taken on the line 2—2 of Fig. 1.

Fig. 3 is a perspective view of the surf board with parts broken away.

Fig. 4 is a cross section on the line 4—4 of Fig. 1 with the pontoons in elevated positions.

Fig. 5 is a cross section similar to Fig. 4 and showing the pontoons in lowered positions.

Fig. 6 is a fragmentary section showing the ratchet and pawl arrangement for holding the pontoons in elevated position.

Fig. 7 is a horizontal section taken on the line 7—7, Fig. 2.

Fig. 8 is a cross section taken on the line 8—8 of Fig. 7.

Fig. 9 is an enlarged vertical section of the rudder, its mounting and electrical contacts associated therewith.

Fig. 10 is an enlarged horizontal section taken on the line 10—10 of Fig. 9.

Fig. 11 is a detail sectional view of a mercury switch which may be used in the ignition circuit of the engine.

Referring by numerals to the accompanying drawings which illustrate a preferred embodiment of my invention, 10 designates the hollow watertight body of the surf board having a rounded bow 11, in which is formed a well or vertical opening 12, for the accommodation of a propeller driving shaft and its housing 13.

The lower portion of this housing projects below the bottom of body 10 and carries a propeller 14, driven by the shaft within said housing, and

protected by a surrounding guard or cage 15, preferably of wire.

A motor 16, preferably an internal combustion engine, of the conventional marine type, used for propelling small boats, drives the shaft within housing 13, said motor being positioned above well 12 and detachably connected, by suitable clamps to a rail 17, located on the deck of the surf board just in front of said well.

10 The clamping means just referred to, comprises a pair of short plates 18, pivoted at 19 to rail 17 and notched for the reception of housing 13 and exhaust pipe 20, and the rear ends of these plates being held in clamping engagement with parts 13 and 20 by a releasable latch 21 (see Fig. 7).

These clamping plates in addition to securing the engine to the deck of the surf board, provide a closure for the upper end of well 12 and thereby prevent water from splashing upward through said well.

Connected by hinges 22 to the sides of the deck 10^a of the surf board, are pontoons 23, preferably elongated cylindrical shells of sheet metal or the like, which lie alongside said surf board and connecting the forward portions of said pontoons, is a transversely disposed retractile coil spring 24, which tends to maintain said pontoons in elevated positions as seen in Fig. 4. When so positioned the pontoons are wholly above the surface of the water.

When the pontoons are swung outwardly and downwardly so as to lie on the surface of the water and thereby add to the buoyancy of the surf board, spring 24 is expanded so as to store power therein and said pontoons are held in such positions by detents 25, adjustably mounted on the sides of the deck, and which engage ratchet fingers 26, secured on the pontoons (see Fig. 5).

The steering means for the surf board include a rudder 26, positioned beneath the bow 11 and carried by the lower end of a shaft 27, mounted for a rotary and slight tilting movement in a bearing 28, that is formed in the lower end of a vertical housing 29, secured on the forward end of said bow.

45 Shaft 27 is normally held at its forward limit of tilting movement within housing 29 by a spring 30, secured to said housing and bearing against the front side of said shaft. Mounted on the 50 rear face of shaft 27 and insulated therefrom is a contact 31, which when said shaft is tilted rearwardly, engages a contact 32 mounted on and insulated from housing 29 (see Fig. 9).

55 Contacts 31 and 32 are connected by suitable conductors 33 to the ignition system associated

with engine 16 and due to the pressure of spring 30 against shaft 27, so as to separate contacts 31 and 32, the ignition circuit is normally open.

Mounted on the upper end of shaft 27 is a transverse steering arm 34, to the ends of which are connected the ends of a cord 35 which extends rearwardly over the surf board.

Thus a person sitting, lying, or standing on the surf board may grasp the substantially parallel portions of the cord and readily shift the position of the rudder to steer said surf board and as long as said cord is held taut, the contacts 31 and 32 are engaged so as to close the ignition circuit of the engine.

If desired the exposed contact form of switch may be replaced by a mercury switch as shown in Fig. 11, and where this construction is used, a substantially bow shaped tube 36 of glass containing a small body of mercury is pivoted on housing 29, so that its inner end is engaged when shaft 27 is tilted rearwardly by pull on the steering cord.

When this engagement takes place, tube 36 is tilted so that the drop of mercury runs to the lowered outer end of said tube and thereby connects contacts 37, in the ignition circuit.

Connected to the speed control of the engine, is a rod 38, the outer end thereof terminating directly above the axis of shaft 27 and being connected to the lower end of a short crank 39, which depends from a rock shaft 40, mounted in bearings 41 on steering arm 34.

The opposite end of shaft 40 is provided with an upstanding crank arm 42, to which is connected the forward end of a cord 43 which extends rearwardly over the surf board adjacent the right hand portion of cord 35 and being connected thereto by several spaced transverse cords 44.

The construction just described provides simple means for actuating the accelerator of the engine while the surf board is being driven.

Operation of the engine drives propeller 14, which in turn drives the surf board forwardly and rudder 26 is turned by pulling strains applied to one side portion or the other of cord 35, thus steering the board during forward travel. Speed of the engine and propeller 14 driven thereby, may be increased as desired, by pull upon cord 43.

When the surf board is being driven by one person, the pontoons 23 are elevated as shown in Fig. 4, thus cutting down water resistance and enabling the board to be driven at higher speeds.

To increase the buoyancy of the surf board, so as to carry two or more persons, the pontoons, are lowered into the positions shown in Fig. 5.

Thus it will be seen that I have provided a power driven surf board that is simple in structure, inexpensive of manufacture and very effective in performing the functions for which it is intended.

It will be understood that minor changes in the size, form and construction of the various parts of my improved surf board may be made and substituted for those herein shown and described without departing from the spirit of my invention, the scope of which is set forth in the appended claims.

I claim as my invention:

1. In a power driven surf board, the combination with an elongated hollow body provided in its forward portion with a vertical opening, of a motor disposed above said opening, a propeller driven by said motor and disposed below said opening, a rudder disposed beneath the forward end of said body, manually operable means for actuating said rudder and pontoons hinged to the sides of said body so as to swing upwardly and inwardly onto the sides of the deck of said body and a retractile spring connecting said pontoons.

2. In a power driven surf board the combination as set forth in claim 1, with manually operable means associated with said rudder actuating means for actuating the speed controlling means of said motor.

3. In a power driven surf board the combination as set forth in claim 1, with cooperating pivoted cover plates for clamping a portion of said motor and for closing the upper end of said well.

4. In a power driven surf board the combination as set forth in claim 1, with pontoons hinged to the sides of said body and adjustable means for securing said pontoons in different vertical positions.

5. In a power driven surf board the combination as set forth in claim 1 with independently operable means carried by said rudder actuating means for controlling the ignition circuit of said motor.

6. The combination with a surf board and its deck, of a motor actuated propeller for driving the surf board, pontoons disposed to the sides of and hinged to said deck so as to swing upwardly into position on top of said deck and a retractile spring connecting the forward portions of said pontoons.

DOTY M. STEELE.
